UNITED STATES PATENT OFFICE.

JEAN FRANÇOIS GEVAERTS, OF SUDBURY, ONTARIO, CANADA.

BUTCHER'S BLOCK SCRAPER.

Application filed April 11, 1925. Serial No. 22,279.

To all whom it may concern:

Be it known that I, JEAN FRANÇOIS GEVAERTS, a subject of the King of Great Britain, and a resident of Sudbury, in the Province of Ontario, Canada, have invented certain new and useful Improvements in Butchers' Block Scrapers, and do hereby declare that the following is a full, clear, and exact description of the same.

10 My invention relates to improvements in butchers' block scrapers, and more particularly to a power-actuated scraper.

15 The object of my invention is to devise a scraper of simple form, easily manipulated, very rigid, and effective in action.

20 To this purpose, I have shown in the accompanying drawings various views of this device and in every view, the same letters of reference refer to same parts throughout.

25 Figure 1 is a view of my scraper in working position on a butcher's block;

Figure 2 is a front view thereof;

Figure 3 is a central section;

30 Figure 4 is a detail showing how the scraping brushes are attached; and

35 Figure 5 is a view of the motor and the adjustable standard thereof, showing their relation with the butcher's block.

40 Referring more particularly to Figure 5, 1 is a standard, here shown with three legs supported on casters 2. 3 is an electric motor to which is fastened a rod 4. This rod is slidingly mounted in the standard, which is hollow for that purpose. In order to

45 adjust the height of the motor to the height of various butchers' blocks, I provide a set screw 5 on the standard to hold the rod 4. 6 is a flexible shaft shown in broken sections, and 7 is the scraper which is enclosed in a casing 8 made in two sections, the rear face 9 thereof forming a flange integral with the sleeve 10, covering the brush shaft 11 and serving as a hand-piece as well. This shaft is mounted in casing 10 in bearing 12 which,

50 in the present instance, is in the form of a bushing retained in position by a set screw 13. Shaft 11 is provided outside bearing 12 with an eye 14 into which the flexible shaft 6 is fastened. Shaft 11 also has a bushing 15 forming a bearing adjacent the flange 9. This bearing is kept in place by a set screw 16.

55 Onto the shaft 11 adjacent the bearing 15 a brush core 17 is mounted. This core is preferably fastened to shaft 11 by means of a key 18. The core is surmounted by a

metal cylinder 19 formed in sections and fastened to the same by means of screws 20. This sectional cylinder is perforated as at 21 to receive a plurality of steel bristles 22. These bristles are mounted on the cylinder by passing through the openings 21 and their inner ends are turned at right angle so that they rest against the brush core, as shown in Figure 4. It will be understood that such perforations extend all around the cylinder and that a great number of steel bristles are mounted around the core 17.

60 The brush so constructed is enclosed in a casing 8, preferably made in one piece and having a handle 24 and a bearing 26 formed of a bushing 27 mounted in a projection in the casing, this bearing being retained by set screws 28. The casing 23 is fastened to flange 9 by means of thumb screws 29. It will be understood that a section of the periphery of the casing is open, as at 30, to allow the brush bristles to project outside the same.

65 In order to regulate the contact of the bristles with the block, I provide a gauge 31 mounted in a bracket 32 on the casing. This bracket 32 is perforated to receive a bolt 33 which projects from the gauge 31, and intermediate same and the bracket a spring 34 is mounted. The bolt is threaded at its upper end and held in position by means of a nut 35. The opposite side of the gauge is hinged as at 36 to the casing, as shown in Figure 2. By this construction, the gauge is resilient and allows the bristles to more or less engage the block according to the pressure applied on the casing.

70 Referring again to Figure 5, it will be seen that the motor is connected to the scraper by means of a flexible shaft and that in order to dispose the motor to the right height according to the block to be scraped, it is adjustably mounted vertically as heretofore explained.

75 In operation, the scraper is placed on the butcher's block and the motor adjusted to the height required. The operator holds the scraper by means of handle 24 and sleeve 10, and moves the same over the block, when the steel bristles will readily engage the block according to the pressure the operator places on the scraper and remove not only the accumulated material on the same but will act more or less as a planer to even its 80 surface.

When not in service, the machine may be stored away by using the handle 24 as a hanger.

In the present showing, I have described one form of such scraper which has given very good results but it should be understood that I reserve the right to any changes coming within the scope of my invention and covered by the following claim:

- 10 In a butcher's block scraper of the class described, in combination, a motor, means to adjust the height of said motor, a flexible shaft extending from said motor, a rotary scraper mounted on a shaft to which said flexible shaft is connected, a core on said shaft, sectional cylinders mounted on said core, a plurality of perforations in said sec-

tional cylinder, steel bristles mounted in said perforations having their inner ends bent at right angles so as to rest against the 20 brush core, means to fasten said sectional cylinder on said core, a casing over said brush into which said shaft is mounted, an opening in said casing, a gauge surrounding said opening having one side hinged to the 25 casing and the other having a bolt passing through a bracket in the casing, and a spring between the gauge and the bracket to cause the said gauge to move resiliently vertically.

In testimony whereof, I have hereunto affixed my signature, this 23rd day of July, 1924, at Sudbury, Ontario.

JEAN FRANÇOIS GEVAERTS.
